UNITED STATES PATENT OFFICE.

CHRISTIAN LORENZEN, OF BERLIN-NEUKOLLN, GERMANY.

PROPELLION OF AIRCRAFT.

Application filed August 16, 1923. Serial No. 657,807.

To all whom it may concern:

Be it known that I, CHRISTIAN LORENZEN, a citizen of the German Republic, residing at Berlin-Neukolln, Germany, have invented 5 certain new and useful Improvements in the Propulsion of Aircraft, of which the following is a specification.

The means of propulsion for aircraft—motor and propeller—are calculated for a 10 normal density of air (1 atm.), at which the highest efficiency is attained. With the decrease of density at increased heights the motor and propeller lose correspondingly in efficiency, and consequently the machine does 15 not attain the speed which she otherwise might do in the case of decreased density of air in view of the decrease in air resistance.

For overcoming this drawback motors 20 have already been employed on the one hand whose efficiency remains constant with all densities of air, for example motors which are furnished with a compressor plant operated by an exhaust gas turbine 25 and connected with the intake of the motor, which brings the more or less densified outer air fed to the motor to normal atmospheric pressure. On the other hand propellers with variable pitch have been employed, whereby the inclination of the 30 blades is capable of adjustment in accordance with the variation of air density. Both the motor and the propeller then require, however, the continual observation of the 35 pilot who, with the greatest amount of attention, will not find it possible to effect the control of same with such regularity that in the constantly varying air density a constant efficiency of the motor is attained and 40 a corresponding pitch given to the propeller. There are, therefore, always differences in the turning moment of motor and propeller.

The present invention consists in regulating by automatic organs the constant efficiency of the motor and the variable pitch of the propeller in uniformity with one another, the operation of these organs being effected by the factor governing the efficiency of the propeller and motor, namely the density of the air prevailing at the time, which thereby represents the combinatory element between motor and propeller.

For this purpose the motor and propeller, or the control valve in the intake of the motor and the adjustment rod for the pro-

peller blades respectively, are made dependent upon membranous organs reacting upon the air density, which are arranged in such a manner that the efficiency of the motor remains constant and the pitch of the propeller varied simultaneously and automatically with every density of air. 60

The motor and propeller are therefore so regulated in continual agreement by the air itself that the efficiency always remains 65 constant, whereby the aircraft is able to fully employ the advantage of decreased density of air with regard to its speed.

The invention more particularly consists in arranging the membranous organs operating the adjustment rod for the propeller blades and the regulation valve in the intake of the motor in such a manner that their reaction upon the alteration in air density can be varied in agreement. In this manner 70 it is possible, naturally with corresponding construction of the motor and propeller, for increasing the efficiency of the motor to induct to the same a mixture of over 1 atm. and to adjust the pitch of the propeller accordingly. The constancy of this high efficiency 75 of the motor and the corresponding regulation of the pitch of the propeller is then effected automatically and in agreement as 80 previously described. 85

In the drawing—

Figs. 1-3 illustrate the membranous organs operating the adjustment device for the propeller blades;

Fig. 4 shows in plan and section the membranous operating organ for the regulating valve in the intake of the motor;

Fig. 5 shows the complete arrangement of the propulsive means for aircraft according to the invention. 95

The membranous operating organ of the adjustment device for the propeller blades consists of a container in which is imprisoned an amount of air of the density prevailing at sea level. The cover of the container is formed as a membrane or a piston or secured to a resilient tube in such a manner that it has a certain possibility of movement. This container rotates in conjunction with the propeller, and the movement 100 of the cover operates through suitable means upon the adjustment device. 105

1, 1 is the axis of rotation of the propeller shaft 2. The vertically standing blades 3, 3 rotate in bearings 4, 4. The ad- 110

justment rod 5, 5 engages at the points 6, 6 of the blades. The rods 5 are secured to a plate 7, which represents the cover of the container 8 with the imprisoned air. Between the cover 7 and the cylindrical wall 9 of the container 8 is connected a resilient membrane 10, which consists of an undulated sheet of metal or other suitable resilient organ.

- 10 In the container 8 the pressure is 1 atm., obtained for example by connecting the container with the outer air when the machine is at sea level and then permanently closing same. If the outer pressure decreases by the 15 fact that the machine has attained a higher altitude the air imprisoned in the container 8 forces the cover outwardly until it has reached an extent where all the forces working upon the cover 7 are counterbalanced. 20 This movement draws upon the rods 5, and the blades are rotated round the point 4 in such a manner that the pitch is increased. If the outer pressure again decreases by the descent of the machine an alteration in the 25 pitch of the blades is again effected by the retraction of the cover 7, etc. The whole device is provided for protection with the hood 11.

As it is the air pressure itself which regulates the pitch of the propeller, the latter, if the amount of imprisoned air is correctly calculated, must always be capable of producing a uniform turning movement at all densities, so that the efficiency corresponds 35 to the constant efficiency of the motor. In this manner the pilot is no longer burdened with the adjustment of the propeller.

The membranous organ for operating the regulating valve in the intake of the motor 40 is illustrated in Fig. 4. 12, 12 is the valve, which opens and closes the openings 13, 13 for the air proceeding to the intake 14 of the motor from the compressor plant. The passage of the air from the compressor plant 45 to the intake 14 is shown by an arrow. The valve plates 12, 12 are located upon a valve rod 15, the one end of which is attached to a membranous container 16. This container 16 is filled with air at 1 atm. pressure and 50 closed from the outside. It is located in a container 17, which is connected with the intake of the motor, so that the same pressure prevails therein as in the intake. The container 16 is suspended in suitable manner in 55 the container 17, for example on to the cover 18, the container 17 being moreover closed from the outside. If the pressure in the intake and consequently in the container 17 decreases, the air in the membranous organ 60 16 expands and the valve 12, 12 is opened, so that the air from the compressor can enter the intake. When the pressure here has correspondingly increased the container 16 will again be retracted and the valve is 65 closed.

Fig. 5 shows the whole arrangement of the aircraft propulsion according to the invention. The propeller is furnished with the membranous regulating organ described, likewise the motor with the membranous 70 regulating organ for the regulation valve in the intake thereof. Air at a higher pressure is fed to the regulating valve from the compressor plant 20 of a gas turbine 21 through a conduit 19, the gas turbine being operated 75 by the discharge gas of the motor 22 and drawing in the air through the conduit 23. In the case of flying machines which are only intended to attain moderate heights of 20000-26000 feet it is sufficient to employ a 80 device as illustrated in Fig. 4. The membranous organ 16 is thereby mounted in a container 17 closed from the outside, and the intake 14 runs directly into the intake system of the motor. For machines which are to fly at greater altitudes of 30000-50000 feet the container in which the membranous organ is mounted is preferably sufficiently 85 large for simultaneous reception of the whole motor and all passengers upon the 90 machine. The intake 14 is then, as illustrated in Fig. 3, open towards the space 24 formed by the body of the machine and closed up from the outside. The motor 95 draws in air from this space. Naturally, the container 17 serving for reception of the membranous container 16 is likewise open towards the space 24.

If the regulating valve, as described above, is adjusted for a normal air density, i. e., 100 for 1 atm., the air proceeding from the compressor and having a higher pressure will be converted into a uniform pressure for the motor of 1 atm., and the motor operates with a constant efficiency in agreement with 105 the above-described corresponding adjustment of the propeller pitch.

It has been shown that by the employment of a discharge gas turbine and the compression of the air effected in stages 110 the air cannot only be brought to atmospheric pressure at the greatest heights available for travelling, which are between 50000 and 56000 feet, but also greatly beyond this. The compressor even in these heights 115 delivers air at a higher pressure than 1 atm. The invention makes use of this fact in the manner that a suitable adjustment device 120 25 is mounted upon the membranous organ 16 operating the regulating valve, which device, for example by adjustment of the point of suspension of the container 16 in the container 17, permits variation in the reaction of the membrane 16 upon the density of the air in the intake. The adjustment device, which merely needs to consist of a simple adjuster, permits the adjustment of the regulating valve in such a manner that, for example, it already opens 125 when the pressure in the intake falls below 130

1½ atm. In this manner the pilot, by regulation of the reaction of the membrane 16 upon the density of air, can obtain as high a pressure as desired in the intake within 5 the limits of the capabilities of the compressor. Naturally, for this a corresponding construction of the motor is necessary in such a manner that same is capable of employing a mixture of over 1 atm. If such 10 a device is provided upon the membranous organ for the operation of the regulating valve the space in the flying machine is preferably divided into two compartments by the wall 26, of which, the compartment 15 24 is employed for mounting the motor with its accessories, fuel, etc., whilst the rear space 27, which is only filled with air of 1 atm. for which a second similar regulating valve 28 is employed, serves for 20 reception of the passengers.

If, in this manner, the efficiency of the motor is varied by regulation, the pilot must also be able to correspondingly adjust the propeller. For this purpose the hollow 25 space of the container 8 which is located on the propeller hub is, for example, connected to a labyrinth packing 29 and a pipe conduit 30 extending to the pilot's seat. By the pilot's seat is located a small air pump 30 31. By manipulation of the latter the pilot is able to vary the amount of air underneath the piston according to choice, and hereby bring the pitch of the propeller into accordance with the particular turning 35 moment of the motor.

What I claim is:—

1. The combination with aero-plane propulsion means including a propeller and a driving motor having an air intake of means 40 functioning automatically to effect simultaneous regulation of the air intake and the pitch of the propeller blades to com-

pensate for variations in the density of the surrounding air and in such manner as to maintain the motor and the propeller at 45 constant efficiency irrespective of the density of the surrounding atmosphere, said means comprising sealed containers each imprisoning air at a definite pressure, said containers being capable of contraction and expansion 50 and being exposed externally to the pressure of the surrounding atmosphere, and means responsive to expansion and contraction of said containers for regulating the intake of the motor and simultaneously 55 varying the pitch of the propeller blades.

2. The combination with an aero-plane motor having an air intake of means functioning to automatically regulate said intake in such manner as to maintain the 60 motor at constant efficiency irrespective of variations of density of the surrounding air, said means comprising an outer casing open to the atmosphere, a sealed inner container 65 imprisoning air at a different pressure and exposed externally to the atmospheric pressure of the outer container, said inner container being capable of expansion and contraction in response to variations of the atmospheric pressure, valve means operating 70 in said air intake and a connection between said valve means and said container whereby opening and closing of the valve means is controlled by expansion and contraction of the container. 75

3. The combination with the structure of claim 2 of means for regulating expansion and contraction of said container in response to the variation of the atmospheric pressure. 80

In testimony whereof I have affixed my signature.

CHRISTIAN LORENZEN.
